UNITED STATES PATENT OFFICE.

OTTO SCHULTZ, OF BERLIN, GERMANY.

JOINING METAL RODS AND BARS.

SPECIFICATION forming part of Letters Patent No. 687,660, dated November 26, 1901.

Application filed December 23, 1899. Serial No. 741,457. (No model.)

To all whom it may concern:

Be it known that I, OTTO SCHULTZ, manufacturer, a subject of the King of Prussia, German Emperor, residing at Berlin, in the 5 Kingdom of Prussia, Germany, have invented certain new and useful Improvements in Joining Metal Rods and Bars, of which the following is a specification.

My invention relates to an improved method 10 of joining or securing together metal bars and rods for forming grates and the like. Heretofore such bars have been joined or united together either by welding or by means of rings, rivets, or screws.

15 My invention consists in forming an opening in one bar, inserting the other bar in said opening, bending said bar on opposite sides of the opening, and then subjecting the bar with the opening to pressure, all as hereinafter fully described, and pointed out in the claims.

A practical embodiment of the invention is represented in the accompanying drawings, forming a part of this specification.

25 Figure 1 is a side and cross-sectional view of one bar or rod to be united. Fig. 2 is a side elevation and a cross-sectional view of the other bar or rod. Fig. 3 is a side elevation, partly in section, showing one bar inserted in 30 the opening of the other bar and before they have been secured together. Fig. 4 is a similar view showing the parts joined or united. Fig. 5 is a plan view of the same. Fig. 6 is a side view of one bar, showing it provided with 35 differently-shaped openings. Figs. 7 and 8 are respectively a side view, partly in section, and a side view of different forms of bars secured together; and Fig. 9 is a plan and side view, partly in section, showing a plurality of 40 bars united to a single bar.

Referring to Figs. 1, 2, 3, 4, and 5, *a* is a flat bar of iron, and *b* a T-iron, to which the bar *a* is to be secured at right angles. The T-iron *b* is provided in its web and adjacent 45 to the base with the oblong opening *c*, and the edge of the web opposite the opening *c* is formed with a bulge or enlargement *d*, as clearly shown in Fig. 2. To join or secure

the bars together, the bar *a* having been inserted in the opening *c* of the T-iron, as 50 shown in Fig. 3, the bar *a* is bent on opposite sides of the web of the T-iron into contact with the base thereof, as shown in Fig. 4, and then the T-iron is subjected to pressure of the bulge or enlargement *d*, to flatten the 55 same, and thereby contract the opening *c*, when the parts will be firmly and securely joined or united together.

Instead of flat bars bars of other shapes may be united or joined to the T-iron, and 60 when such bars are used the opening in the T-iron is to be of the same shape as the bars.

In Fig. 6 the T-iron *e* is shown provided with round, square, and V-shaped openings *f* *g* *h*, thus permitting correspondingly-shaped 65 bars to be secured thereto. In Fig. 7 a flat bar *a'* is secured in an angle or L iron *i*, and in Fig. 8 a round bar *j* is secured to a flat bar *k*.

In Fig. 9 I have shown several bars united 70 to a T-iron. In this case the T-iron *o* is formed with an opening of a size equal to that 75 of the combined bars or pieces *l m n*. It is to be understood that the center bar or piece *m* is to be inserted in the opening after the other bars or pieces *l n* have been placed in position.

When light or small bars or rods are to be united, it will not be necessary to heat them, as they can be readily bent while cold; but in the case of large or thick bars they will have 80 to be heated and secured together while hot.

I claim—

1. The method herein described of uniting a rod or bar with an angle-iron, consisting in inserting the rod or bar in an opening of one 85 member of the angle-iron, said opening being of the shape of the bar or rod, bending the rod or bar on opposite sides of the said member into contact with the imperforate member of the angle-iron, and finally subjecting 90 the member of the angle-iron having the opening to pressure to contract the said opening, as set forth.

2. The combination of an angle-iron having an opening in one member a short distance 95 from its other member, and a bar or rod of

the shape of the opening in the angle-iron and arranged therein, said rod or bar being bent on opposite sides of the member through which it passes into contact with the imper-
5 forate member, as set forth.

3. The combination of a T-shaped iron having an opening in its web a short distance from its base and a plurality of bars fitting in the opening of the angle-iron and each bent

on opposite sides of the web into contact with 10 the head of the T-iron, as set forth.

In witness whereof I have hereunto signed my name in the presence of two subscribing witnesses.

OTTO SCHULTZ.
